AUDITING MACHINE

Filed June 14, 1924

FIG. 2

FIG. 1

UNITED STATES PATENT OFFICE

WILLIAM H. ROBERTSON, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

AUDITING MACHINE

Application filed June 14, 1924. Serial No. 720,049.

This invention relates to auditing machines, and more particularly to machines adapted to receive a plurality of detachable destination devices, such as shown in Letters Patent of the United States, No. 1,593,599, issued to the present inventor on July 27, 1926, for railroad ticket printing machines.

One object of this invention is to provide a machine which will print the data appearing on each of a plurality of detachable destination devices.

Another object is to so construct the device that the insertion of one of the said devices will operate all the mechanism of the machine.

With these and incidental objects in view, the invention consists of certain novel features of construction and combinations of parts, the essential elements of which are set forth in appended claims and a preferred form or embodiment of which is hereinafter described with reference to the drawings which accompany and form part 25 of this specification.

Of said figures:

Fig. 1 is a section taken through the machine just inside the left hand side frame.

Fig. 2 is a detail view of the eccentric for controlling the impression hammer.

Fig. 3 is a top plan view of the machine with the cabinet removed.

Fig. 4 is a facsimile of a fragment of the detail strip printed by the machine.

Fig. 5 is a bottom plan view of the type carried by each of the destination devices.

Fig. 6 is a detail view of the mutilated gear and the cooperating mechanism which feeds the detail strip.

40 *General description*

This machine is designed for use particularly with the ticket printing system described in the above mentioned patent. In 45 that system there are used a plurality of detachable destination devices adapted to be inserted in the machine, and those devices upon the operation of the machine, print the name of the destination, the consecutive 50 number of the ticket issued and the price,

There is one of these devices provided for each station to which it may be necessary to issue a ticket.

At the end of any specified period, such as a week or a month, it is desirable to have 55 the destination devices in each station audited by a representative of the railroad company. The machine disclosed in this application is adapted to be used by the auditor to facilitate his work. The machine 60 contains a detail strip suitably supported by storage and receiving rollers, and fed a certain distance on every operation of the machine. An ink ribbon is provided for inking the type when an impression is to be 65 made. In addition to this mechanism, there is a consecutive number counter operated to add "1" on every operation of the machine.

When an audit is to be made, the auditor 70 simply takes the destination devices appropriate to the stations and inserts them, one after the other, into the auditing machine. The machine is so designed that the insertion of a destination device will operate 75 the entire machine to accomplish all the functions thereof.

Destination devices

The destination devices adapted to be 80 used with this machine are shown and described in detail in the above referred to patent and, therefore, only a very brief description thereof will be included herein. Each of the devices (Fig. 1) comprises a 85 rectangular box 30, from each side of which projects a pin 31. Extending upwardly from the top of the box is a key stem 32 carrying a cap 33 marked with the name of the destination appropriate to the particular device. On its lower surface the device carries two electroplates 34 (Fig. 5) adapted to print the name of the station and the price of the ticket. The devices also carry 95 a plurality of consecutive number type wheels 35 advanced one step for each ticket printed by the device. Two vertical guides 36 and 37 are provided for cooperating with the respective pins 31 of the destination de- 100

vices and guiding these devices on their insertion.

Detail strip mechanism

5 When one of the devices is inserted in the auditing machine an impression is taken therefrom onto a detail strip. The mechanism for supporting and feeding the detail strip will now be described. The detail strip 40 is fed from a storage roll 41 loose on a shaft 42, supported by the side frame, over a roller 43 loose on a stud 44, then beneath the inserted destination device and over a second roller 45 loose on a stud 46, 10 to a receiving roll 47 loosely mounted on a shaft 48 supported by the side frame.

15 Integral with the receiving roll 47 is a disk 49 which has a flange 50. Cooperating with the inner periphery of the flange 50 is a roller 51 loosely mounted on a pin carried by a clutch hanger 52, pivoted on the shaft 48. The roller 51 is normally forced toward the left, as seen in Fig. 1, by a spring-pressed plunger 53 carried by the hanger 52. The roller 51 lies between the inner periphery of the flange 50 and a surface 54 on the hanger 52. When the hanger 52 is rotated counter-clockwise about the shaft 48, the roller 51 will jam between the 20 surface 54 and the inner periphery of the flange 50 of the disk 49, and rotate the disk and the receiving roll counter-clockwise for the detail strip with the hanger 52. When this hanger is rotated clockwise, however, 25 the roller 51 moves toward the right, against the tension of the plunger 53, into the enlarged portion of the opening between the surface 54 and the flange 50, and will, therefore, have no effect on the receiving 30 roll.

35 The means for rotating the hanger 52 to advance the detail strip will now be described. The hanger 52 carries a pin 55 which lies in the path of a finger 56 of a mutilated gear 57 loose on the shaft 48. The teeth of this gear mesh with a segment 58 carried on a downwardly extending arm of a bell crank lever 59 loose on a stud 60 supported by the side frame. The other 40 arm of the bell crank lever 59 is forked as at 61, at its outer end and is adapted to cooperate with the left hand one of the pins 31 projecting from the sides of each of the destination devices. An arm 62, 45 connected to the bell crank lever 59 by a hub 63, is forked at its outer end similar to the fork 61 to cooperate with the pin 31 on the right hand side of the inserted destination device.

50 It can be seen, therefore, from Fig. 1 that when a destination device is inserted in the auditing machine, that is, placed in position and pushed downwardly, the upper arm of the bell crank lever 59 and the arm 55 55 62 will be rocked clockwise, due to the en-

gagement of the pins 31 with the forked ends 61. The movement of the bell crank lever, through the segment 58 carried thereby, will rotate the mutilated gear 57 counter-clockwise. As the finger 56 of the mutilated gear is normally in contact with the pin 55 carried by the hanger 52, this hanger will also be rocked counter-clockwise with the mutilated gear and, as this movement takes place, the roller 51 will become 70 jammed between the surface 54 and the inside periphery of the flange and will thereby carry the feeding roll 47 counter-clockwise far enough to remove the printed area of the detail strip effected during the last 75 previous operation from beneath the destination device, and provide a blank space on the detail strip to receive the impression from the inserted destination device.

80 The destination device is inserted in the machine and then removed. It is evident that as it is removed the pins 31 acting upon the forked ends of the bell crank 59 and arm 62, will return the connected parts to the positions shown in Fig. 1. Mechanism 85 is provided for returning the hanger 52 to the position shown in Fig. 1, and this mechanism is as follows: Loosely mounted on the shaft 48 is a collar 64 having a finger 65 normally in contact with the pin 55 previously described. A torsion spring 67 is coiled around the shaft 48, one end being fastened to the finger 56 of the mutilated gear 57, and the opposite end being fastened to the finger 65 of the collar 64. It is evident, therefore, that when the mutilated gear 57 is positively returned to the position 90 shown in Fig. 1, by the withdrawal of the destination device last inserted, the finger 65, being connected to the finger 56 by the 95 spring 67, will cause the hanger 52 to be rotated to its normal position, as shown in Fig. 1.

100 A means is also provided herein for proportionately shortening the distance of feed 105 given to the detail strip as the quantity of paper on the receiving roll increases. The mechanism for accomplishing this function is well known and forms no part of the present invention. An arm 70 (Figs. 1 and 110 3) is loose on a stud 71 projecting from the frame, and its end 72 is bent at right angles. The end 72 is normally held in contact with the paper on the receiving roll by a spring 73, stretched between a pin on an arm 74 115 connected to the arm 70 by a yoke 75, and at its opposite end to a pin projecting from the side frame. The arm 74 carries a roller 76 in the same plane as a tail 77 integral with the hanger 52. When there is no paper 120 wound on the receiving roll, the parts will occupy the positions shown in Fig. 1. As the paper accumulates on the receiving roll, however, the arm 70 will be rocked clockwise, which will also rock the arm 74 to a 125 130

like extent due to the yoke connection 75. This clockwise movement of the arm 74 positions the roller 76 so that as the hanger 52 is returned to its normal position by the 5 spring actuated collar 64, the tail 77 of the hanger 52 contacts the roller 76 sooner than it would with the parts in the positions shown in Fig. 1. It can, therefore, be seen that as the paper on the receiving roll increases, the amount of feed given to the receiving roll, through the member 52, will be proportionately less, thereby maintaining an even spacing of the items on the detail strip.

Means is provided for inking the type of the destination device when an impression is taken therefrom. This consists of an ink ribbon 66 which passes about a suitable ink roller 68 and is then led upwardly between the platen 95 and the type. Any desired means may be included for feeding the ink ribbon, but as this forms no part of the invention none is shown herein.

Means are also provided to prevent any 25 retrograde movement of the flanged disk 49 and the receiving roller 47 when the hanger 52 is moved clockwise to its normal position after a feeding movement has taken place. The means for accomplishing this 30 object comprises a detent arm 80 loose on a stud 81. The arm 81 carries a roller 83 which normally lies between the inner periphery of the flange 50 of the disk 49 and a laterally projecting flange 84 of the arm 80. 35 The arm 80 carries a roller 82 which rests on the outside of the flange 50 and prevents any clockwise movement of said arm. A spring-pressed plunger 85 normally holds the roller 83 in contact with both the flange 40 50 and the surface 84. It can be seen that when the disk 49 is rotated counter-clockwise to feed the detail strip, this movement will not affect the roller 83. If, however, as the hanger 52 returns to its normal position, there is any tendency of the disk 49 45 to be carried with it, the roller 83 will wedge itself between the flange 84 of the detent arm 80 and the inner periphery of the flange 50, thereby preventing any movement of the 50 disk in a clockwise direction.

Impression mechanism

After the detail strip has been fed, as above described, to bring a blank portion 55 of the strip beneath the destination device, an impression is taken therefrom in the following manner: The platen 95, formed of any suitable material, is carried by a laterally extending angular bed 96 integral 60 with one arm 97 of a bell crank lever 98 loosely mounted on a stud 99 projecting from the side frame. The bell crank lever 98 is provided with a broad bearing 100 (Fig. 3) to reduce wear and resultant lost motion.

As the destination device is pushed down-

wardly, upon its insertion in the machine, the bell crank lever 98 is rocked clockwise due to the engagement of the pins 31 with the forked ends 61 of this lever and arm 62. Pivoted to one arm of the bell crank lever 75 59 is a downwardly extending thrust bar 101 having a shoulder 102 cooperating with a flattened stud 103 carried by the arm 97 of the bell crank lever 98. The thrust bar 101 normally tends to rock in a counter-clockwise direction (Fig. 1), due to a spring 104 stretched between the lower end of the thrust bar and a pin on the side frame. This movement is, however, prevented by the contact of the lower end of the thrust bar 101 75 80 with the eccentrically pivoted end of an arm 105 mounted in the side frame of the machine.

It can be seen from Fig. 1 that as the destination device is pushed downwardly, the thrust bar 101 will rock the arm 97 of the bell crank lever 98 counter-clockwise. Due to the fact, however, that the thrust bar 101 moves downwardly, while the bell crank lever 98 has an arcuate movement about the 85 90 stud 99, a point will be reached in the operation when the stud 103 will pass out or escape from beneath the shoulder 102 of the thrust bar 101. When this occurs, the bell crank lever 98 which carries the platen 95 95 will be rapidly rotated in a clockwise direction by a spring 106 stretched between an extension 107 of the bell crank lever 98 and a pin projecting from the frame. The platen 95, being thus released, will strike the 100 detail strip and take an impression from the type of the inserted destination device on the strip.

An adjustment is provided to vary the point at which the shoulder 102 of the 105 thrust bar 101 will pass out or escape from contact with the stud 103. In order to accomplish this function, one end of the arm 105, above mentioned, is eccentrically mounted with relation to its pivot. The other end of the arm 105 carries a set screw 108 (Fig. 2) which projects through an arcuate slot 109 formed in the side frame. It is evident that by loosening the set screw 108, the arm 105 can be turned about its 110 pivot, which movement, due to the eccentric mounting of this arm, will adjust the thrust bar 101 slightly to the right or left, as viewed in Fig. 2. If the adjusting arm 105 is rotated counter-clockwise to the extent 115 of the slot 109, it can be seen that the thrust bar 101 will be rocked clockwise a short distance. Therefore, when the destination device is pressed downwardly, the parts will not have to travel to the same extent, as they would, if the adjustment was as 120 shown in Fig. 2, before the shoulder 102 will pass out of or escape from contact with the stud 103 to permit the platen to move upwardly and take an impression.

Consecutive number mechanism

A consecutive number counter is provided and is operated on every operation of the machine. It consists of four counter wheels 110 loosely mounted on a shaft 111 supported by the side frame. These counter wheels are visible to the operator through a glass plate 112 which covers an opening in the top of the cabinet.

Pivoted on the shaft 111 is a pawl carrier 113 which carries a differentially timed feeding pawl 114, the first tine of which cooperates with a ratchet wheel 115 fast on the units counter wheel. The pawl carrier 113 has a notch 116 formed therein, through which projects a pin 117 carried by an upwardly extending arm 118 of the bell crank lever 98. It will be recalled that the bell crank lever 98 is rocked first counter-clockwise, and then clockwise on every operation of the machine and, through its connection with the pawl carrier 113, this pawl carrier and the pawl 114 receives a clockwise and then a counter-clockwise rotation. On the clockwise rotation of the pawl carrier 113, the first tine of the pawl 114 turns the ratchet wheel 115 and the units counter wheel 110 one space. On the return movement of the pawl carrier 113, the pawl passes over the teeth of the ratchet. A ratchet similar to the ratchet 115 is fastened to the side of each of the counter wheels 110 and the transfer from wheels of lower to those of higher denomination is effected by means of a transfer mechanism of the deep notch variety, which it is not believed to be necessary to describe herein. Cooperating with each of the ratchet wheels 115 is a spring pressed retaining pawl 120, pivotally mounted on a rod 121 (Figs. 1 and 3).

A knurled knob 122 is fast to the end of the shaft 111 and may be manually rotated when it is desired to reset the consecutive number counter to zero.

Operation

The operation of this machine is extremely simple. All that it is necessary for the auditor to do is to place the destination devices, one at a time, in position in the machine; press them down to their full extent, and remove them. The downward movement of the destination devices will cause the detail strip to be fed to bring a blank space thereon into position to be printed on. This movement will also cause the impression to be made and the consecutive number counter to be actuated. As the devices are withdrawn, all of the parts are returned to their normal positions. When the operation is finished, the detail strip may be removed and it is evident that comparison of the strip with the strip printed on the last

previous occasion, when the devices were audited, will show by the difference in the consecutive numbers of the devices of each station the number of tickets that have been issued to each station.

The ticket printing devices 30 are inserted and removed one by one through the opening in the casing of the auditing machine, and the upper prong of the forked ends of the arm 62, and bell crank 59 are shorter than the lower prongs thereof, as shown in Fig. 1, to prevent obstructing the insertion of the ticket printing devices. As a ticket device 30 is inserted in the casing, its laterally projecting pins 31 seat in the forks 61 and rock the bell crank 59 and arm 62 clockwise, inward travel of the ticket device being arrested by the feet at the lower ends of the guides 36, which lie in the paths of the pins 31.

Obviously, by the time the pins 31 have been arrested by the feet, the shoulder 102 of the thrust bar 101 has slipped off the stud 103 of the impression lever 97, which has rocked upwardly in clockwise direction under tension of the spring 106 to effect the printing, so that the stud 103 lies some distance above the shoulder 102 on the thrust bar 101.

Due to the arcuate travel of the paper feeding bell crank 59, and arm 62, the forks 61 thereof, have fitted themselves over the pins 31 on the ticket devices, so that as the ticket device 30 is withdrawn from the recess in the casing, the pins 31 rock the bell crank 59 and arm 62 in counter-clockwise direction to restore these elements, and as the bell crank 59 restores, it draws the thrust bar 101 upwardly until the shoulder 102 thereof lies above the stud 103, whereupon the spring 104 snaps the shoulder over the stud preparatory to the next operation.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the class described, the combination of a record receiving medium, impression means, and a plurality of detachable devices, the insertion and depression of which directly actuates said impression means to produce an impression from said devices on said medium.

2. In a machine of the class described, the combination of strip feeding mechanism, a detachable device carrying type, and means directly actuated by the insertion and depression of said device for operating said feeding mechanism and taking an impression from said type.

3. In an auditing machine, the combination of a plurality of detachable devices carrying type, a printing medium, means for feeding said medium, printing means co-operable with said type, a counter, and means directly actuated by the insertion and depression of any one of said devices for operating said printing and feeding means, and adding one unit to said counter. 70
10. 4. In a machine of the class described, the combination of an impression and feeding means, an insertable destination device, pins carried thereby, a bell crank lever actuated by one of said pins upon the insertion and depression of said device, and means actuated by said bell crank for operating said impression and feeding means. 75
15. 5. In a machine of the class described, the combination of an impression and feeding means, an insertable destination device, pins carried thereby, a bell crank lever actuated by one of said pins upon the insertion and depression of said device, a segment gear carried by said lever, means actuated by 80
20. 25. said gear for operating said feeding means, a member pivoted to said lever, and means actuated by said member for actuating said impression means. 85
25. 6. In a machine of the class described; the combination with a paper feeding mechanism enclosed in a casing; and a normally discharged impression means; of a type carrier insertable into and removable from the casing; and means directly operated by the 90
30. 35. type carrier as it is inserted into the casing to cock the impression means. 95
40. 7. In a machine of the class described; the combination with a casing having an opening formed therein; paper feeding mechanism within the casing; and normally discharged impression means within the casing; of a type carrier insertable into and removable from the casing through the opening; and mechanism directly operated by the type 100
45. 50. carrier as it is inserted into the casing, to 105
55. 60. cock the impression means and to actuate the paper feed mechanism. 110
55. 65. 8. In a machine of the class described; the combination with a normally discharged impression means; of means to cock the impression means, said cocking means traversing a path tangent to the arcuate path traversed by the impression means whereby the impression means after being cocked escapes the cocking means to effect an imprint; a 115
60. 65. manually-operated member to actuate the cocking means; and an adjustable guide for said cocking means, the adjustment of which varies the point at which the impression means escapes the cocking means. 120
65. 70. 9. In a machine of the class described; the combination with a normally discharged impression means; of a projection on the impression means, said projection traversing an arcuate path upon operation of said im- 125
70. 75. 80. 85. 90. 95. 100. 105. 110. 115. 120. 125. 130.

In testimony whereof I affix my signature.

WILLIAM H. ROBERTSON. 115
